(57) **CLAIM**

We claim the ornamental design for a dental cart system, as shown and described.

DESCRIPTION

FIG. 1 is a side perspective view of a dental cart system;

FIG. 2 is a side view of FIG. 1;

FIG. 3 is a side view of FIG. 1;

FIG. 4 is a front view of FIG. 1;

FIG. 5 is a rear view of FIG. 1;

FIG. 6 is a top view of FIG. 1; and,

FIG. 7 is a bottom view of FIG. 1.

The features shown in broken lines depict environmental subject matter only and form no part of the claimed design. The broken away symbols in the drawings indicate the appearance of any portions of the article between the break lines forms no part of the claimed design.
